CLAIM

The ornamental design for a nonwoven fabric, as shown and described.

DESCRIPTION

FIG. 1 is an isometric view of a nonwoven fabric showing our new design;

FIG. 2 is a plan view thereof;

FIG. 3 is an isometric view of a second embodiment of our new design; and

FIG. 4 is a plan view thereof;

FIG. 5 is an isometric view of a third embodiment of our new design; and,

FIG. 6 is a plan view thereof.

The pattern of the design repeats uniformly throughout the surface of the nonwoven fabric. The claimed surface of the nonwoven fabric is flat and planar. The rear of the design forms no part of the claim. The broken lines forming an edge surrounding the design represent the boundaries of the nonwoven fabric and form no part thereof.
